UNITED STATES PATENT OFFICE.

KINTARO MIYANAGA, OF SEATTLE, WASHINGTON.

ENVELOP.

1,090,639.

Specification of Letters Patent. Patented Mar. 17, 1914.

Application filed April 21, 1913. Serial No. 762,639.

To all whom it may concern:

Be it known that I, KINTARO MIYANAGA, a subject of the Emperor of Japan, and a resident of the city of Seattle, in the county of King and State of Washington, have invented certain new and useful Improvements in Envelops, of which the following is a specification.

My invention relates to envelops and has for its objects the provision of a novel form of closure and envelop, whereby the latter may be securely closed without applying an adhesive therebetween, and the formation of the envelop which facilitates the opening of the same.

For a full understanding of the present invention reference is to be had to the following description and the accompanying drawing wherein—

20 Figure 1 is an elevation of an envelop in its opened position embodying my invention. Fig. 2 is a fragmentary elevation thereof in which the envelop is partly closed, and Fig. 3 is a similar view showing the manner in which the envelop is finally sealed.

With particular reference to the drawing, 1 designates the front side of the envelop body, 2 and 3 the side flaps and 4 the bottom flap, the first noted side flap projecting beneath its companion member, and the bottom flap overlapping the adjacent end portions of the flaps 2 and 3. Adjacent the opposite end of flap 2, and cut therefrom, is a retaining or locking tab 5 adapted to engage over an edge of a closure flap 6 carried by the adjacent edge of the front 1. This flap 6 has an inclined edge 7, extending outwardly from the front 1 and completely across the latter, which is adapted for engagement by tab 5 when the flap 6 is closed over the mouth of the envelop. On its larger end portion, flap 6 is provided with an offset tongue 8 adapted to overlie the front 1, when the said flap is engaged beneath tab 5, to be securely fastened to said front by the postage stamp, as most clearly disclosed in Fig. 3.

50 A slit 9 is provided between flap 2 and front 1 communicating with the mouth of the envelop. This slit is adapted to be closed by tongue 8 and is for the purpose of inserting the finger or instrument beneath flap 6 for removing the latter from under tab

5 after releasing the tongue. Tongue 8 is provided with an extension 8' adapted to project below the stamp to facilitate the opening of the closure, as is obvious.

Having thus described my invention, what I claim as new, and desire to secure by Letters Patent of the United States of America, 60 is:—

1. An envelop comprising a body provided with a mouth and a slit leading from the mouth for the insertion of an opening implement, and closure means for the mouth 65 of the body provided with an angular extension for closing the slit in said body.

2. An envelop comprising a body provided with a mouth and a slit leading from one end of the mouth in a fold of the body, 70 a closure flap on the front of the body for the mouth thereof, said flap being adapted to engage over the back of the body, and a tongue on one side edge of the flap for closing the slit in the body and adapted to engage over the front of the body. 75

3. An envelop comprising a body portion having a mouth and a slit adjacent the mouth, a retaining tab on one side of the body, a closure flap for the mouth of the 80 body adapted to engage by a springing action under the tab, and a tongue carried on the side edge of the flap and adapted to engage the opposite side of the body from the tab, close the slit in the body and be secured 85 to the latter.

4. An envelop comprising a body provided with a mouth and a slit leading from the mouth, a closure flap joined to the body for closing the mouth thereof by folding 90 thereover, the free edge of the flap being inclined, relative to the edge joined to the body, to provide a wide side edge on the flap adjacent the slit in the body, a tongue carried on the last edge of the flap and 95 adapted to engage the opposite side of the body from that engaged by said flap for closing the slit, and a retaining tab on the body for engaging over the free edge of the flap. 100

Signed at Seattle, Washington, this 9th day of April 1913.

KINTARO MIYANAGA.
